UNITED STATES PATENT OFFICE.

ALEXANDER FREDERICK JENKINS, OF BALTIMORE, MARYLAND.

RADIATOR TRAP.

Application filed December 4, 1920. Serial No. 428,414.

To all whom it may concern:

Be it known that I, ALEXANDER FREDERICK JENKINS, a citizen of the United States of America, residing in the city of Baltimore, State of Maryland, have invented certain new and useful Improvements in Radiator Traps, of which the following is a specification.

The use of steam traps of various types for draining the condensed water from the radiators in domestic and similar heating systems of the types known as vacuum vapor and steam heating systems, is well known. The majority of these are actuated by a diaphragm exposed on one side to the pressure of steam or condensed water and on the other to a liquid or gas having a high co-efficient of expansion.

The radiator trap which is the subject of this invention belongs to this general type but embodies a radical improvement in that instead of a diaphragm or metal bellows, the actuating member consists of a tube of any suitable cross section bent in a series of reverse curves or otherwise formed in a series of transverse peaks and depressions.

Change of pressure inside the tube or change of the relation of the internal to the external pressure causes change of the length of the tube. Increase of the ratio of the internal pressure to the external pressure causes elongation of the tube.

As compared to the previous apparatus of this general type, the device of the invention has the advantages of cheapness and simplicity of construction, both as to the actuating member and the co-operating parts. Another important advantage is the compactness of the structure, its sensitiveness and efficient operation, particularly in its effective response to small changes of pressure and temperature.

In the accompanying drawing, I have illustrated a radiator trap embodying my invention in the form in which it has been reduced to practice and which is regarded as the preferred form.

Figure 1 is a vertical section on the line of the axis of the device.

Figure 2 is a horizontal section on the line 2-2, Figure 1.

Referring to the drawings by numerals, each of which is used to indicate corresponding parts in the different figures:

The radiator trap illustrated, consists of a seat or body member, 1, and a co-operat-

ing cap, 2, adapted to engage the seat member in any suitable manner as at 3, an actuating member, 4, in the form of a reverse curved tube and a valve, 5. The base or seat member, 1, has a passage, 7, adapted to be connected to the radiator at the low point thereof and referred to hereinafter as the radiator passage and a passage, 8, intended to be joined to the return pipe of the system and referred to hereinafter as the return passage. The base member, 1, includes a valve seat, 9, and above the valve seat is the pressure chamber, 10, to which the radiator passage, 7, leads. The passage, 8, is likewise connected to the pressure chamber leading downward therefrom by way of the valve seat, 9, which is in the bottom wall of the chamber and faced upward. The valve, 5, co-operates with the valve seat, 9, and in the form of the invention shown opens upward. The valve, 5, as shown, is provided with guiding means, 6, depending therefrom and engaging the walls of the passage below the seat, serving to align the valve as it approaches the seat and co-operating with the valve rod, 21, to this end. The pressure chamber, 10, in the seat member, 1, is open at the top of the casting of which the seat member is formed and said opening, 11, is covered by the actuating member, 4, which is placed in upright position on a shoulder, 12, in the base casting surrounding the opening, 11, the actuating member being formed with a base flange, 13, surrounding the opening for this purpose, so that the tube or actuating member forms part of the pressure chamber. Above the shoulder, 12, the base member is formed with internal threads, 14, and the cap, 2, has its end portion, 15, threaded to co-operate with the threads, 14, forming the aforesaid engagement or connection, 3, the cap being screwed down against the flange, 13, holding the actuating member in upright position within the cap, as aforesaid.

Surrounding the actuating member within the cap occupying the space indicated by reference character, 16. I preferably place the fluid, i. e., a liquid or gas having a high co-efficient of expansion or this may be introduced by way of the plugged opening, 17, or otherwise.

The actuating member, 4, in the preferred form as shown consists of a tube closed at one end at 18, flanged at the other end at

13, and bent in a series of reverse curves having alternate transverse peaks, 19, and depressions, 20, the sides being parallel, the general direction of the tube being straight. 5 The peaks are spaced apart to permit the valve rod, 21, to which the valve, 5, is secured to reciprocate in the tube. While the tube is referred to as bent in a series of reverse curves, the exact nature of the curvature is immaterial, the essential feature being that the tube is bent in a series of peaks and depressions. The valve rod, 21, is secured to the actuating member at a point spaced from the point of support at 13. It 15 is most conveniently secured to the closed end wall, 18, of the tube in the present instance by a nut, 22, on a reduced end, 23, of the rod drawing a shoulder, 24, on the rod against the bottom surface of the wall, 18. 20 In operation, the passage, 7, as aforesaid, is joined to a low point on the radiator and passage, 8, to the return pipe of the system. When the inside of the radiator is filled 25 with dry steam or vapor at the desired temperature and the radiator is drained of water, the steam or vapor at the said temperature fills the actuating member or tube, 4, and communicates substantially the same temperature to the liquid in the space, 16, which tends to expand applying pressure to the outside of the tube, and causing the 30 valve to be and remain seated. When the temperature of the radiator drops causing condensation, the water at a lower temperature accumulates in the actuating member or tube, 4, cooling the expansible liquid or other fluid in the space, 16, and causing decreased external pressure which causes a proportionate or corresponding excess internal 35 pressure as compared to the external pressure, elongating the tube or actuating member and raising the valve, 5, from its seat which causes the condensed water to drain from the radiator into the return pipe. 40 Examination of the structure shows that on account of the small cross section of the actuating member, which takes the place of the ordinary diaphragm, the trap may be made of exceedingly small dimensions; that 45 the manner of mounting it between the cap and the base and of connecting it to the valve reduces the number of parts to the minimum and that the actuating member, 4, as well as the entire trap may be produced 50 at a comparatively small cost which is an important element as these traps must be supplied in large quantities, one being used in connection with each radiator; also the use of such a tube as an actuating member 55 gives an exceedingly large throw of the valve for a small change in pressure which results in the production of a trap which drains immediately on the accumulation of even a small quantity of water and which 60 closes as promptly, preventing the escape 65 of steam or other heat vehicle used in the system from the radiator.

In Figure 2, which is a cross section on line 2-2 of Figure 1, I have shown the actuating or translating member formed of two strips, 25 and 26, bent transversally to form the concave cross sections illustrated and the longitudinal edge flanges, 27. These strips are bent in corresponding longitudinal reverse curves as illustrated in Figure 75 1 and then placed with the curves in registration, the flanges being in contact and secured together by any suitable means as brazing, welding, soldering or riveting or the tube may be otherwise formed as by 80 bending an ordinary tube.

I have thus described specifically and in detail a radiator trap embodying my invention in the preferred or present form in order that the nature and operation and manner of applying the invention may be clearly understood; however, the specific terms herein are used descriptively rather than in a limiting sense, the scope of the invention being defined in the claims. 90

What I claim and desire to secure by Letters Patent, is:

1. A radiator trap having an actuating member consisting of a tube bent in the form of alternate peaks and depressions, the opposite sides of the tube forming the peaks and depressions, being substantially parallel and so spaced and related as to admit a valve rod inside the tube and permit it to be reciprocated longitudinally therein, a valve rod in said tube, a valve on said rod, and a valve seat with which the said valve co-operates. 95

2. A radiator trap having a pressure chamber and connections to connect the same to a radiator, a tube having parallel sides bent in a series of peaks and depressions joined to the pressure chamber so that the inside of the tube forms part of the chamber, a valve seat leading from the chamber, a valve co-operating therewith and means connecting the valve to the tube at a point remote from the attachment of the tube to the chamber, a chamber enclosing the tube and an expansible fluid confined therein. 110 115

3. A radiator trap having a pressure chamber adapted to be connected to a radiator outlet, a tube bent in a series of peaks and depressions having one end connected to the pressure chamber so that the inside of the tube forms part of the chamber, the opposite end of the tube being closed, a valve seat leading from the bottom of the pressure chamber, a valve co-operating therewith, having its stem extending through the tube and secured to the closed end of the tube, a member enclosing the tube forming a chamber about the same, and an expansible fluid confined therein. 120 125

4. A radiator trap consisting of a body 130

member having a pressure chamber therein, means for connecting said chamber to a radiator outlet, the pressure chamber being formed with a valve seat and a shoulder 5 above the valve seat, a tube formed in a series of peaks and depressions, having one end open and flanged, the flanged end being seated on the shoulder, the other end of the tube being closed, a detachable cap 10 adapted to co-operate with the body member so that the cap can be caused to enclose the tube providing a chamber about the tube the cap engaging the flange on the tube and holding it in position, and a valve co-operating with the seat and having a stem extending into the tube and secured to the closed end of the tube.

5. A radiator trap having a valve cham-

ber adapted to be connected to a radiator outlet, a tube closed at one end and open at the other end, and bent in the form of alternate peaks and depressions, the opposite sides of the tube being substantially parallel, the open end of the tube being connected to the said valve chamber, a valve rod inside the tube and secured to the closed end of the tube, the valve rod extending through the tube, a valve in the valve chambers secured to the rod, and guiding means for the valve.

Signed by me at Baltimore, Maryland, this 1st day of December, 1920.

ALEXANDER FREDERICK JENKINS.
